UNITED STATES PATENT OFFICE

167,867

VENTILATOR HEAD FOR GAS PIPE LINES OR THE LIKE

Thomas Dixon Sedberry and Arthur Fleet Davis,
Shreveport, La.

Application February 3, 1950, Serial No. 7,726

Term of patent 14 years

(Cl. D62—3)

To all whom it may concern:

Be it known that we, Thomas Dixon Sedberry and Arthur Fleet Davis, citizens of the United States, residing at Shreveport, in the parish of Caddo and State of Louisiana, have invented a new, original, and ornamental Design for a Ventilator Head for Gas Pipe Lines or the like, of which the following is a specification, reference being had to the accompanying drawing, forming part thereof.

The single figure is a perspective view of a ventilator head for gas pipe lines or the like showing our new design.

We claim:

The ornamental design for a ventilator head for gas pipe lines or the like, as shown.

THOMAS DIXON SEDBERRY.
ARTHUR FLEET DAVIS.
